TELEPHONE HOLDER AND RECEIVER
LIFTER

George J. Rovnak, Campbell, Ohio

Application November 5, 1945, Serial No. 626,780

5 Claims. (Cl. 179—146)

1

This invention relates to a device for lifting a receiver of a telephone.

The principal object of the invention is the provision of a remotely controlled device for lifting the receiver of a telephone instrument.

A further object of the invention is the provision of a device incorporating a telephone supporting member and an associated device for mechanically lifting the receiver of a telephone positioned thereon.

A still further object of the invention is the provision of remote control means for a telephone, said remote control means counterbalancing a telephone receiver.

The invention shown and described herein has been devised to form a simple and efficient means of remotely controlling the receiver of a conventional telephone such as a hand set wherein the transmitter and receiver are incorporated in a single unit of the telephone, which device includes a stand mountable on a vertical surface such as a wall upon which the telephone may be positioned and movable means affixed to the said stand normally registering with the telephone and between the base portion thereof and the receiver-transmitter unit thereof.

A flexible actuating cable is mechanically connected to the movable receiver-transmitter moving means and with a remote control unit which may be located a considerable distance away from the telephone. The remote control unit includes a counterweight for offsetting the weight of the transmitter-receiver unit of the telephone and means for moving the counterweight so as to impart similar movement to the transmitter-receiver unit of the telephone.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a side view of the telephone supporting stand and transmitter receiver apparatus and a remote control means associated therewith with parts broken away and parts in cross section.

Figure 2 is a front view taken on line 2—2 of Figure 1.

Figure 3 is an enlarged detail view of the remote control apparatus shown in Figure 1 and taken

2

on line 3—3 of Figure 1 and with parts broken away and parts in cross section.

By referring to the drawings and Figure 1 in particular it will be seen that a vertical surface such as a wall 10 serves as a support for a stand 11, an outwardly extending portion 12 of which is adapted to receive and support a telephone hand set such as shown in dotted lines in Figure 1 and indicated generally by the numeral 13. The stand 11 is mounted on the wall 10 by means of screws 14 and has an upwardly extending bracket 15 positioned on an upper surface thereof which in turn pivotally supports a lever 16 pivoted to the upper end of the bracket 15 by means of a pivot 17. One end of the lever 16 is cut away to provide a thinner section engageable beneath the transmitter-receiver unit of the telephone 13. The transmitter-receiver unit is shown in dotted lines in Figure 1 and is indicated by the numeral 18.

The opposite end of the lever 16 extends beyond the pivot point 17 toward the wall 10 and is pivotally connected by means of a pivot 19 to an L-shaped connecting link 20, the horizontal portion of which is connected to a vertically positioned rod 21. The rod 21 is positioned through an opening 22 and has an eyelet 23 formed on its lowermost end which serves as a means of affixing one end of a flexible cable 24 thereto. An opening 25 formed in the lower portion of the stand 11 in alignment with the opening 22 heretofore described permits the flexible cable 24 to pass downwardly therethrough, and, in the particular installation of the telephone holder and receiver lifter disclosed in Figure 1, the flexible cable 24 passes downwardly to and through a floor indicated by the numeral 26 and over a pulley 27 positioned therebeneath.

It will thus be seen that the telephone 13 is positioned on the extending portion 12 of the stand 11 which in turn has been affixed to the wall 10, the transmitter-receiver unit 18 of the telephone 13 will rest on the telephone 13 and its switch mechanism as well as on the extending end portion of the lever 16, as heretofore described. Thus, the weight of the transmitter-receiver unit 18 will hold the lever 16 downwardly and also open the switch mechanisms incorporated in the telephone 13.

It will further be seen that at such time as the flexible cable 24 is moved downwardly with relation to the stand 11, movement will be transmitted to the transmitter-receiver unit 18 of the telephone by way of the connecting link 20 and the pivot 19 to the lever 16 which in turn, pivot-

ing upon the pivot 17 on the upper end of the bracket 15, will lift the transmitter-receiver unit 18 of the telephone so as to permit the switch mechanism in the telephone 13 to be disengaged by the transmitter-receiver unit 18.

By referring to Figure 2 of the drawings it will be seen that the outwardly extending portion 12 is supported by a pair of angle brackets 28 which are affixed to the stand 11 and the outwardly extending portion 12 thereof as by means of rivets 29. It will also be seen that the upstanding bracket 15 is preferably U-shaped so that the lever 16 which is also U-shaped is supported between the upstanding arms of the U-shaped bracket 15 on the pivot 17. The connecting link 20 is also U-shaped and is positioned with the lever 16 lying between the upstanding arms thereof and pivoted thereto by the pivot 19 thus providing a durable structure capable of satisfactorily performing its purpose.

By referring again to Figure 1 of the drawings it will be noted that the flexible cable 24 may be trained over a plurality of pulleys 27 to a desired remote location such as, for example, a horizontal distance beneath the floor 26 and a vertical distance thereabove as by extending the flexible cable 24 upwardly as through a hollow partition such as indicated by the numeral 30. A pair of pulleys 27 may be arranged at the desired vertical distance to guide the flexible cable 24 out of the hollow partition 30. A remote control unit shown in the left hand portion of Figure 1 and also in enlarged detail in Figure 3 is provided for imparting and controlling the movement of the cable 24 and hence the lever 16 heretofore referred to.

By referring to the left hand portion of Figure 1 of the drawings and to Figure 3 it will be seen that the remote control unit comprises a cylindrical casing 31 having upper and lower caps 32 and 33, respectively, threadably engaged thereon, the upper cap 32 having an opening 34 centrally located therein through which the flexible cable 24 is passed. Slidably positioned within the cylindrical casing 31 there is a weight 35 which is provided with a pair of upward extensions 36 which support a cross member 37 to which the flexible cable 24 is affixed. The cylindrical casing 31 is provided with a slot 38 in one side thereof and the weight 35 is provided with a projecting pin 39 which registers with the slot 38 and extends outwardly therethrough. The weight 35 is preferably formed of lead or similar heavy material and is sufficient to balance the combined weight of the lever 16 and the transmitter-receiver unit 18 of the telephone.

It will thus be seen that when it is desired to lift the telephone transmitter-receiver unit 18 as, for example, in answering an incoming call and for the purpose of stopping the ringing of the bell of the telephone 13, the pin 39 of the remote control unit may be moved downwardly along the slot 38 in the cylindrical housing 31, which motion will be conveyed by the flexible cable 24 trained over the plurality of pulleys 27 and eventually imparted to the lever 16 which will raise the transmitter-receiver unit 18 of the telephone thereby obtaining the desired action.

The remote control unit is preferably affixed to stationary objects such as the partition 31 by means of one or more U-shaped clamping members 40, which members are provided with openings through which screws 41 may be driven.

It will thus be seen that a simple and efficient device has been disclosed which may be installed

between any two desired points in a building such as a dwelling house and will serve in use to hold a telephone of the hand set type and provide remotely actuated means for lifting the transmitter-receiver unit portion of the telephone hand set from engagement with the switch mechanism of the telephone when desired.

Having thus described my invention, what I claim is:

10. 1. A telephone supporting and actuating device including a platform for the reception of a telephone instrument, a lever pivotally mounted on said platform and engaging the transmitter-receiver unit of the said telephone and a remote control unit for the said lever, the said remote control unit including a slotted tubular casing, a counterweight disposed in said casing and pin means on said counterweight for raising and lowering the same, and a flexible cable connecting the said counterweight in the remote control unit with the said lever.
15. 2. The combination with a telephone support of a lever movably affixed thereto and positioned thereabove for engagement with the transmitter-receiver of a telephone positioned on the said support, and remotely positioned means for actuating the said lever, said means including a slotted tubular casing and a counterweight positioned in said casing for vertical movement and pin means engaging the said counterweight and extending through said slotted casing for imparting manual movement to said counterweight, and a flexible cable connecting the said counterweight and the said lever with one another.
20. 3. The combination of a supporting bracket for a telephone hand set having a lever pivoted thereto and positioned thereabove for engagement beneath the transmitter-receiver unit of a telephone hand set positioned on said supporting bracket and a remote control unit operatively connected thereto, the said remote control unit comprising a stationary tubular casing having a weighted member reciprocally mounted therein, a slot in the said tubular casing and a pin in the said weighted member registering with the said slot and extending therethrough, a flexible cable connecting said lever and said weighted member, the said weight being movable downwardly as by manual movement imparted to the said pin to move the said lever and the transmitter-receiver unit of the telephone hand set upwardly and out of engagement with the said telephone.
25. 4. In a telephone receiver actuating device having a pivoted member engaging said telephone receiver, a remote control unit comprising a cylindrical casing having caps threadably affixed to its ends and means for mounting the same in a vertical position on a supporting surface, a longitudinally extending slot formed in the said cylindrical casing and a weight reciprocally positioned in the said cylindrical casing and a pin in said weight engaging the said slot and extending outwardly therethrough, a cable attached to the said weight and extending out of the said cylindrical enclosure and attached to said pivoted member for operating the said telephone receiver actuating device.
30. 5. A telephone receiver actuating device comprising a shelf-like member for attachment to a vertical surface and having a portion thereof spaced with respect to the said vertical supporting surface and another portion thereof projecting therefrom and adapted to receive the said telephone, an upward extension formed on the

said shelf-like member and a lever pivoted thereto, the said lever extending outwardly above the said telephone supporting surface for registry between the said telephone and the transmitter-receiver portion thereof, a remote control unit for the said lever comprising a cylindrical casing, a weight reciprocally mounted in said casing, a slot in said casing and a pin in the said weight extending through the said slot, and cable means connecting the said weight with the said lever and a plurality of pulleys over which the said cable is trained, the said weight adapted to be moved by the said pin and to hold the said lever and the telephone transmitter-receiver unit in elevated relation to the said telephone.

GEORGE J. ROVNAK.
